UNITED STATES PATENT OFFICE

ALEXANDER HERON, OF DELAWARE, ONTARIO, CANADA.

CAR-COUPING.

SPECIFICATION forming part of Letters Patent No. 399,532, dated March 12, 1889.

Application filed April 14, 1887. Serial No. 234,837. (No model.)

To all whom it may concern:

Be it known that I, ALEXANDER HERON, a subject of the Queen of Great Britain, and a resident of Delaware township, in the Province of Ontario, Canada, have invented certain new and useful Improvements on Car-Couplers, of which the following is a specification.

This invention relates to a device for coupling cars together in a train, and one which is simple in construction and reliable and durable in operation, and one which can be adjusted and set instantly in such a manner that the cars may be coupled when they come together, or come together and part again without coupling, as required, and the operation of adjusting and setting the coupler to couple the cars is performed at the side out from between the cars, so that the operator will not be exposed to any danger from accident of any kind when adjusting and setting my improved coupler; and this invention consists of the improved construction and combination of parts of the same, as will be hereinafter more fully described and claimed, reference being had to the accompanying drawings, wherein—

Figure 1 is a side elevation of two draw-bars, partly in section, attached to two adjacent cars, and showing their position when coupled together. Fig. 2 is an enlarged detail perspective view of the coupling pin or link. Fig. 3 is a detail perspective view of a modification of Fig. 2. Fig. 4 is an end elevation of a car and draw-bar, showing the devices which revolve the draw-bar and the draw-bar in the position both draw-bars and links are when coupled together. Fig. 5 shows one of the draw-bars in position to uncouple or to receive the coupling pin or link when coupling. Fig. 6 is a plan view, partly in section, showing the flanges on the entering end of one coupling link or pin engaging with the shoulders of the adjacent coupling link or pin.

A designates the platform, and B B' the floor-beams, of the car, in which the draw-bar C is held in place, and this draw-bar C may be open or closed on the top, as required. Part of the draw-bar C is formed round in cross-section, as shown at C', where it is sup-

ported in the floor-beam B, to permit said draw-bar and coupling link or pin F held therein to be revolved laterally to couple with or uncouple from the draw-bar of the adjacent car.

55 D is a rod secured to the draw-bar C. This rod D extends through the floor-beam B', and on each side of this floor-beam B' springs E E' are held in place on this rod D—the spring E to ease the jar when the draw-bars strike together when shunting or coupling, and the spring E' to ease the strain of the cars on the draw-bars when starting the train.

F designates a link or pin pivoted on the pivot-bolt G, the latter being secured in the draw-bar C, and this link or pin F is formed with an aperture, F', through which the pivot-bolt G passes. This aperture F' is preferably formed larger in cross-section than the pivot-bolt G, to permit the coupling link or pin F 70 to work perfectly free, and to permit the end F² of one of the links to be placed on the ledge C² of the draw-bar, if required, when adjusting the draw-bars and links, so that the cars will couple when they come together. 75 The entering end F² of the link or pin F may be formed integral with the main part F, as shown in draw-bar C, Fig. 1, or it may be secured thereto by a nut, n, screwed on a screw-thread formed on the end F² in the slot F³, as shown in the adjacent draw-bar C⁵ in Fig. 1, so that if this end F² should become accidentally damaged the latter construction presents an easy, simple, and cheap method of renewing said end F².

80 F³ is a slot extending vertically through the center of the coupling link or pin F, and F⁴ is a longitudinal slot through the center of the coupling link or pin F, which terminates in the vertical slot F³. This slot F³ is square 90 in cross-section, and the slot F⁴ is larger in one cross-section than the cross-section at right angles thereto, and the square slot F³ is as large in cross-section as the larger cross-section of the slot F⁴. This forms shoulders 95 F⁵, and behind the portion which is narrowest in cross-section, immediately at the inner end of the slot F⁴; and the entering end F² of the coupling link or pin F in one cross-section is fitted to enter the narrow cross-section of 100

the slot F^4 perfectly free, and the flanges n' , formed integral with the entering end F^2 , will not pass through the narrow cross-section of the slot F^4 , but will freely pass through 5 the larger cross-section of the slot F^4 , and these flanges n' will turn perfectly free in the slot F^3 , so that when one draw-bar, C, and coupling link or pin F, secured therein, is revolved laterally in its bearings in the floor-beams B 10 until the slot F^4 in the coupling link or pin F is in the position shown in Fig. 5, the entering end F^2 of the link or pin F of the opposite draw-bar will freely enter and pass through the slot F^4 into the slot F^3 , because the flanges 15 n' will be opposite the longer cross-section of the slot F^4 . Then by revolving this draw-bar C and coupling link or pin F secured therein to the position shown in Fig. 4 these flanges n' come opposite the narrow part of the slot 20 F^4 in the slot F^3 and engage with the shoulders F^5 to completely couple and lock the draw-bars together. Then by revolving this draw-bar to the position shown in Fig. 5 again the cars are uncoupled and may freely separate, because the flanges n' come opposite the longer cross-section of the slot F^4 . Thus the 25 cars may be coupled or uncoupled, and when the coupling link or pin F of one draw-bar is in the position shown by dotted line x in Fig. 30 1 the cars may come together and part again without coupling.

In Fig. 3 is shown a modification of this link or pin F, which is preferably used when coupling a draw-bar formed with my improvement. 35 To one having the common ordinary link and pin the flanges n' on the end F^2 engage with my draw-bar, as hereinbefore described, and the link is removed from the common draw-bar, and the pin of the common draw-bar is 40 passed through the latter as well as through the aperture O, formed in said modification shown in Fig. 3.

H is a lever pivoted on the end of the car, and I I are rods connecting the lower end of 45 lever H with the draw-bar C, and one or more

of these rods I may be used as required for the purpose of revolving the draw-bar when coupling or uncoupling; and J is a cog-segment, K a dog, and L a spring, &c., for holding the lever in any required position to which 50 it may be adjusted, as well as the draw-bar in connection therewith, to hold the cars together when coupled, or to permit the cars to be coupled or uncoupled, as required.

Each end of each car is intended to be provided with a lever, H, or other suitable operating device and attachments, but at the alternate side on each car, or on the alternate side at each end of the same car, so that the cars may be readily and easily uncoupled or 60 coupled from either side on which the operator may be at that time.

Having thus described my invention, I claim—

1. In a car-coupling, the draw-bars C, formed 65 round in cross-section at C' and revolving laterally in their bearings, in combination with reversible coupling links or pins F, which are secured in and revolve laterally with the draw-bars, and formed with longitudinal oblong 70 slots F^4 , vertical slots F^3 , shoulders F^5 , and entering end F^2 , formed with flanges n' , as and for the purpose set forth.

2. In a car-coupling, the draw-bars C, formed 75 round in cross-section at C' and revolving laterally in their bearings, and reversible coupling links or pins F, which are secured in and revolve laterally with the draw-bars, and formed with longitudinal oblong slots F^4 , vertical slots F^3 , shoulders F^5 , and entering end 80 F^2 , formed with flanges n' , in combination with the lever H, cog-segment J, dog K, spring L, and connecting-rods II, as and for the purpose set forth.

In testimony whereof I affix my signature in 85 the presence of the two undersigned witnesses.

ALEXANDER HERON.
